CLAIM

The ornamental design for a self-supporting live goods cage, as shown and described.

DESCRIPTION

FIG. 1 is a perspective view of a self-supporting live goods cage showing my new design;

FIG. 2 is a front elevation view thereof;

FIG. 3 is a left side elevation view thereof, the right side elevation view being a mirror image thereof;

FIG. 4 is a rear elevation view thereof;

FIG. 5 is a top plan view thereof; and,

FIG. 6. is a bottom plan view thereof.

The broken lines depict environmental subject matter only and form no part of the claimed design.
